GAS LIGHT CLUSTER

Stanley M. Loveless, Kalamazoo, Mich., assignor to
General Gas Light Company, Kalamazoo, Mich.

Filed June 17, 1974, Ser. No. 479,780

Term of patent 14 years

Int. Cl. D26—05

U.S. Cl. D48—23 R

FIG. 1

FIG. 2

FIG. 3

FIG. 4

FIG. 1 is a side elevational view of a gas light cluster embodying my new design;

FIG. 2 is another side elevational view of the gas light cluster embodying my new design with same being taken from a different position as compared to that of FIG. 1;

FIG. 3 is a cross-sectional view taken on a plane below the mounting base;

FIG. 4 is a bottom plan view thereof.

The support is broken away in FIGS. 1 and 2 to indicate indeterminate length.

I claim:

The ornamental design for a gas light cluster, as shown and described.
